MAGAZINE FOR WIRE HOOK BELT LACERS

Herman Koester, Waterbury, Conn., assignor to
The Bristol Company, Waterbury, Conn., a corporation of Connecticut

Application October 10, 1946, Serial No. 702,564

3 Claims. (Cl. 1—49.4)

1

This invention relates to magazines or retainers for use in machines for installing belt-hooks of the "clincher" type, and more especially to a magazine or retainer in which a group of such hooks may be mounted in alignment and suitably disposed with respect to the material in which they are to be attached, prior to application of the clamping and clinching action of a "belt-lacing machine" of a conventional type. Efficient use of wire belt-hooks requires that a plurality of such hooks, preferably mounted on a card or the like, as shown, for example in my co-pending application Serial No. 571,849, filed January 8, 1945, issued on May 20, 1947 as U. S. Letters Patent No. 2,420,783, be simultaneously inserted and clinched in the end portion of a belt in which said hooks are to form an element in a splice or flexible joint. In order that the hooks be maintained in alignment during the clamping process, it is customary to place the mounting card carrying the desired number of hooks in a retainer or magazine, which may be positioned between the jaws of a suitable clamping machine or of a vise, whereupon the desired clamping force is exerted between said jaws and the hooks forced into place and clinched in the material of the belt. The loops formed by the belt hooks are then disengaged from the magazine, leaving an assembly which may be interleaved with a similar assembly on the other end of the belt, and secured in hinged relationship thereto by a suitable rod or pin member.

It is an object of the present invention to provide a retainer or magazine for the above purpose, in which the belt-hooks when inserted shall be maintained in positive alignment prior to, and during, the clamping action of the lacer.

It is a further object to provide such a magazine, in which the hooks shall be retained in place by a clamping action exerted uniformly from end to end of the group of hooks to be installed.

It is a further object to provide a magazine as hereinbefore described in which the clamping force shall be applied symmetrically of the hook assembly, thereby eliminating any tendency of the hooks to be tilted to one side.

It is a further object to provide a magazine as hereinbefore described in which the clamping effort is exerted as a simple compressive force, eliminating rubbing or sliding action, which has been found to have a tendency to abrade smooth surfaces of the hooks and destroy such rust-resistant coating as they may bear.

It is a further object to provide a belt-hook magazine which shall be simple in design, adaptable to a variety of sizes of belt-hooks and styles of lacers, inexpensive to manufacture, and durable under conditions of repeated and continued use.

In carrying out the purposes of the invention, 60

2

it is proposed to provide a belt-hook magazine having separate transverse slots for individual hook members, and having within the lower part of the slotted portion a straight clamping element adapted to be moved therein in a plane containing the center line of the assembly, whereby to clamp the hooks collectively and individually against a straight pin member inserted prior to, and removed after, the operation of the inserting and clinching jaws of the belt-lacing machine with which the device may be used.

The nature of the invention, however, will best be understood when described in connection with the accompanying drawings, in which:

15 Fig. 1 is a partially exploded front elevation of the magazine with portions shown in section; and Fig. 2 is a similar plan thereof.

Fig. 3 and 4 are respective end elevations of the magazine.

20 Fig. 5 is a front elevation of the magazine loaded with belt hooks.

Fig. 6 is a transverse section taken on the line 6—6, Fig. 5, and Fig. 7 is a similar section, but with cam adjusted to locking position.

25 Referring now to the drawings, 10 designates a block of rectangular cross-section and of length somewhat greater than the width of the widest belting with which the magazine is intended to be used. It is formed, preferably, of steel and is provided with a plurality of transverse grooves 11 incised into its upper surface, said grooves being evenly distributed to correspond to the spacing of standard belt hooks as customarily carried on a mounting card. Longitudinally bored through the block toward the bottom or side remote from the grooves 11 is a cylindrical opening 12; and between said opening and the grooves is a rectangular, longitudinal slot 13 which intersects radially the cylindrical opening 12 and extends also through a portion of the respective bottoms of grooves 11. The interior boundary surface of said slot on the side remote from opening 12, is near to, but within, the face or top of the block into which the grooves are cut, and is of semicircular cross-section.

30 35 40 45 50 55

A cam member 15 of axial length somewhat greater than that of the block 10, is provided with cylindrical extremities 16 and 17 turned to fit the bore of the opening 12, and with an intermediate portion 18 of a section cylindrical, or otherwise curved, about an axis eccentric with that of the extremities 16 and 17, so that, as the member 15 is rotated about its longitudinal axis which coincides with that of the opening 12, the portion 18 will act as a cam.

An extended bar 20 of rectangular cross section, and having a thickness to provide a running fit in the longitudinal slot 13 and a length slightly less than that of the cam portion 18 of

the member 15, formed preferably of steel, is adapted to rest with one face upon the eccentric surface of said cam portion 18, whereby, with rotation of the member 15 about its axis, said bar will be displaced radially through a limited distance in the slot 13 within the block 10, tending to approach, or recede from, the curved or semicircular interior surface of said slot.

An extended pin 21, formed preferably of steel rod having a cylindrical section of radius equal to, or slightly less than, that of the curvature of the interior surface of the longitudinal slot 13, the interior surface of the longitudinal slot 13, is provided with one pointed extremity 22 to facilitate its insertion into the slot 13, and an extremity 23 formed into a ring or hook or the like, whereby said pin may be readily manipulated. A radially extending bar 24, suitably fixed to the extremity 16 of the member 15, serves as a crank, and facilitates manual rotation of the latter in operation.

As indicated in the drawings, Figs. 5 to 7, the device is shown with a group of belt-hooks 25 inserted in the grooves 11 and having positioned between their inwardly directed and sharpened extremities a section of belting 26, to which they are to be applied. In Figs. 6 and 7 said belt-hooks and belting are indicated as positioned between jaws 27 which form operative elements in a vise or conventional belt-hook-applying machine, and are adapted to be forcibly moved toward one another through a limited distance.

In operation, reference being had more particularly to Figs. 5 to 7, the member 15 is rotated until the bar 20 is lying in its "lowest" position—i. e. most remote from the grooved surface of the block 10. A group of belt hooks 25 suited to the width of the belting 26 is then placed in the grooves 11 to project through the opening therein sufficiently far that their loops approach the upper surface of the bar 20. The pin 21 is then inserted from the end of the block 10, passing through and being encircled by, the loop portion of each of the belt-hooks. The member 15 is then by means of the bar 24 rotated about its axis, whereupon the portion 18, by virtue of its eccentric or oblique action, will act as a cam, Fig. 7, and cause the bar 20 to be forced into engagement with the bottom portions of the belt-hook loops, which, in turn engage the surface of the pin 21, forcing it into contact with the curved interior surface of the slot 13 to provide a rigid anvil against which the belt-hooks will be solidly clamped with a uniformly exerted straight-line action, symmetrically distributed, and devoid of oblique forces on the hooks and therefore free of abrasive or rubbing action.

With the hooks clamped in place in the block 10, and the belting placed between their pointed ends as shown in Fig. 7 and the whole positioned between the jaws 27, the latter are to be forcibly brought together by means not shown in the drawings, and forming no part of the present invention. The points of the hooks will thereby be forced into and through the material of the belting, and clinched therein, without possibility of displacement of any of the hooks due to the application of the relatively great pressures which are applied. The jaws 27 are then released, the member 15 rotated to remove the clamping action of the bar 20, and the pin 21 withdrawn, after which the end of the belt 26 may be removed from the apparatus with the desired group of hook elements uniformly and securely applied, and adapted to be interleaved with a similar group

(not shown) on the opposite extremity of the belt, and secured thereto in hinged relationship as is well understood, for example, by means of a suitable rod or pin member (not shown).

5 I claim:

1. A magazine for positioning belt hooks preparatory to insertion in a belt, comprising a block portion having in one surface inwardly extending and transversely disposed, mutually adjacent grooves adapted to receive a plurality of said belt hooks in spaced relationship, said block having a slot extending longitudinally therethrough, intersecting said transversely disposed grooves and extending below the respective bottoms thereof, an elongated pin member adapted to be positioned within said slot and to extend transversely of said grooves, whereby to be embraced by the loop portions of said belt hooks, a cam member mounted for angular motion within said body, and a bar element displaceably mounted within the slot of length sufficient to span all of said grooves and adapted to be operatively engaged by said cam member and laterally forced thereby into non-rubbing contact with respective bottoms of said loops to clamp the same individually into lateral engagement with said pin member.

2. A magazine for positioning belt hooks preparatory to insertion in a belt, comprising a block portion having in one surface inwardly extending, 30 mutually adjacent grooves adapted to receive a plurality of said belt hooks in spaced relationship, said block having formed therein a bore cylindrical in cross-section and extending longitudinally through the block, said bore having a lateral extension rectangular in cross-section extending upwardly to intersect the grooves and to a point above the respective bottoms thereof, an elongated pin member adapted to be positioned within said lateral extension to extend transversely of said grooves whereby to be embraced by the loop portions of said belt hooks, a cam member mounted in the cylindrical bore and having cylindrical end portions and an eccentrically disposed intermediate portion integral therewith, said end portions being journaled in end cylindrical bearings of the said cylindrical bore for rotation therein and about a common axis therewith, and a bar element of length corresponding to that of said intermediate portion adapted to lie partly in the said lateral extension and partly between said cylindrical end portions, to be operatively engaged by said intermediate portion and laterally displaced in said lateral extension by rotary motion of said extended cam member, whereby to engage the bottoms of said loops with direct pressure to clamp the same individually into lateral engagement with said pin member.

3. A magazine for positioning belt hooks preparatory to insertion in a belt according to claim 2, wherein the elongated pin member is removably supported in the said body portion.
